LAWN SPRINKLER

John D. Beinert, Babylon, N.Y., assignor to International Patent Research Corp., Moonachie, N.J., a corporation of New York

Filed Sept. 7, 1967, Ser. No. 8,519

Term of patent 7 years

(Cl. D23—7)

FIG. 1

FIG. 2

FIG. 3

FIG. 4

FIG. 1 is a top plan view of a lawn sprinkler showing my new design;

FIG. 2 is a side elevational view thereof;

FIG. 3 is an end elevational view thereof taken from the right hand end of FIG. 1; and

FIG. 4 is an end elevational view thereof taken from the left hand end of FIG. 1.

The essential features of my design reside in those features shown in full lines.

I claim:

The ornamental design for a lawn sprinkler, as shown and described.
